FRONT PANEL FOR A COMPUTER CONSOLE

Paul A. Jenkins, Groton, Mass., assignor to Digital
Equipment Corporation, Maynard, Mass.

Filed Sept. 29, 1972, Ser. No. 296,631

Term of patent 14 years

Int. Cl. D14—02

U.S. Cl. D26—5

FIG. 1

FIG. 2

FIG. 3

FIG. 4

FIG. 5

FIG. 1 is a front perspective view of a front panel for a computer console embodying my new design;

FIG. 2 is a front elevation thereof;

FIG. 3 is a side elevation thereof;

FIG. 4 is a top view thereof; and

FIG. 5 is a bottom view thereof.

The broken line representation of a computer console in FIGS. 1, 3, 4 and 5 is for purposes of illustration only.

I claim:

The ornamental design for a front panel for a computer console, substantially as shown and described.
